Patented Jan. 16, 1962

192,076

SOCK CLAMP OR SIMILAR ARTICLE

Patricia Coughlin, New York, N.Y.
(51-01 39th Ave., Long Island City, N.Y.)

Filed May 18, 1961, Ser. No. 65,221

Term of patent 14 years

(Cl. D17—6)

FIG. 1 is an exploded front perspective view of a sock clamp or similar article showing my new design.

FIG. 2 is a front elevational view of the same.

FIG. 3 is a sectional view taken along line 3-3 of FIG. 2.

I claim:

The ornamental design for a sock clamp or similar articles as shown.
